UNITED STATES PATENT OFFICE.

EMERY S. BAYLEY, OF SPOKANE, WASHINGTON, ASSIGNOR, BY DIRECT AND MESNE ASSIGNMENTS, OF ONE-HALF TO HARRISON A. DENNEY AND ONE-HALF TO ROBERT T. LAURENCE.

CURRENT-MOTOR.

1,111,350.

Specification of Letters Patent. Patented Sept. 22, 1914.

Application filed May 12, 1913. Serial No. 767,193.

To all whom it may concern:

Be it known that I, EMERY S. BAYLEY, a citizen of the United States, residing at Spokane, in the county of Spokane and 5 State of Washington, have invented certain new and useful Improvements in Current-Motors, of which the following is a specification.

This invention relates to current motors 10 and has for an object to provide a motor adapted to be submerged in a flowing stream and presenting improved features for taking power and motion from the motion of the flowing water.

15 A further object of the invention is to provide a submerged current motor having a vertical shaft with horizontally and radially extending shafts extending from the main shaft with blades operating in pairs 20 and mounted upon the radially extending shafts in improved manner to take power from the moving stream.

25 A further object of the invention is to provide improved structure for supporting the radially extending arms and the blades carried thereby.

A further object of the invention is to 30 provide improved means for connecting the radial shafts with the main shaft.

35 With these and other objects in view the invention comprises certain novel constructions, combinations and arrangements of parts as will be hereinafter more fully described and claimed.

40 In the drawings: Figure 1 is a perspective view of the improved current motor removed from supporting frames or structures. Fig. 2 is a transverse sectional view of the improved motor taken on a vertical plane and seen from the down stream side.

Like characters of reference designate corresponding parts throughout the several views.

The improved current motor which forms 45 the subject matter of this application comprises a vertical shaft 10 which may be mounted in any approved supporting framework; here shown for example as suspended from floats 11 by a framework 12 but it is to be understood that any means 50 of submerging the motor within the flowing stream is equally within the scope of this invention. About the central shaft 10 a plurality of rings as 13, 14 and 15 are provided concentric with the shaft and rigidly

connected therewith by means of rods 16 and 17. The rods 16 are connected directly to the lower ends of posts 18 while the rods 17 are connected directly to the lower ends of posts 19 with the ring 14 60 connected to both the tops of the posts 19 and the bottoms of the posts 18, while the ring 13 is connected with the tops of the posts 18 and the ring 15 with the bottoms of the posts 19. By this arrangement a 65 rigid structure connected with the central shaft is provided with the posts 18 and 19 properly spaced vertically and in staggered relation about such shaft. Through the vertical shaft 10 sleeves or pipes 20 and 70 21 near the top are inserted, which said sleeves are squared upon their insides or otherwise proportioned to receive squared or multiangular shafts 22 inserted therein, the opposite ends of said shafts finding 75 bearings in the tops of posts 18 in any approved manner as by forming trunnions 23 thereon which are inserted through said posts. Intermediate the sleeves 20 and the bottom of the shaft other sleeves 24 and 25 80 are also inserted of similar construction and also adapted to receive shafts 26 which likewise are provided with bearing means in the posts 19, as for instance the trunnions 27. 85

Upon the squared or multiangular shafts 22 and 26 blades are secured as 28, such securing means being in any approved manner but preferably by means of ears 29 secured rigidly to the blades and attached to 90 the squared shafts 22 and 26 by means of set screws 30. The ear at the side of the blade adjacent the vertical shaft 10 is so positioned as to abut against the extremities of the sleeves 20 or 24 and to hold such 95 sleeve in position and hold the shafts 22 and 26 in their bearings in the posts 18 and 19. It will be apparent that when the set screws 30 are loosened the shafts 22 and 26 may be slidably moved into the sleeves 20 100 and 24 to displace the trunnions 23 and 27 whereby the shafts may be taken out and replaced or a new blade put in position as circumstances may require.

It will be understood that in operation 105 the current flowing in the direction of the view of Fig. 1 will impinge against the blades 28 at the right hand side of the figure and hold such blades against the rods 16 at the bottom sides to present the broad 110

side to the current but at the opposite side the blades will be feathered or in horizontal position to present little or no resistance to the passage of the current. The blades upon 5 opposite ends of the connected shafts are positioned perpendicularly to each other so that the feathering of the blade upon the left side will assist in turning its companion blade to vertical position while the 10 turning of the blade upon the right side to vertical position will likewise assist in feathering its companion blade. It will be, therefore, apparent that upon one side of the shaft 10 all of the blades will present 15 broad sides to the current while upon the opposite side of the shaft all of the blades will be feathered presenting little or no resistance and that the blades will automatically change from such broad side to feathered position as the structure rotates 20 about its vertical axis.

I claim:

In a current motor, a frame, a vertically

disposed shaft rotatable with said frame, a sleeve rotatable in and extending horizontally and radially from said shaft and having an interior of polygonal cross section, a pair of blade shafts having polygonal 25 inner ends non-rotatively fitted in the ends of said sleeve and having shouldered outer 30 ends rotatively journaled in said frame, blades having ears non-rotatively fitted on 35 said blade shafts to dispose the blades at right angles to each other, and means for securing one of the ears of each blade to its blade shaft in abutting relation with one end of said sleeve to prevent longitudinal movement of the blade shafts out of bearing relation with said frame, substantially as described.

40
In testimony whereof I affix my signature in presence of two witnesses.

EMERY S. BAYLEY.

Witnesses:

HAROLD SCANTLEBURY,
EDNA BROYLES.
